CLAIM

The ornamental design for a side sizer for garment hanger, as shown.

DESCRIPTION

FIG. 1 is a perspective view of a side sizer for garment hanger showing my new design;

FIG. 2 is an alternative perspective view of FIG. 1;

FIG. 3 is another alternative perspective view of FIG. 1;

FIG. 4 is a front elevation view of FIG. 1;

FIG. 5 is a rear elevation view of FIG. 1;

FIG. 6 is a side elevation view of FIG. 1, the opposite side elevation view being a mirror image thereof;

FIG. 7 is a top plan view of FIG. 1; and,

FIG. 8 is a bottom plan view of FIG. 1.
